Primary Examiner — Catherine S Posthauer*Assistant Examiner* — Lynette Marie Sample(74) *Attorney, Agent, or Firm* — Nakanishi IP Associates, LLC**CLAIM**

The ornamental design for a beverage generating device as shown and described.

DESCRIPTION

FIG. 1 is a perspective view of a beverage generating device,

FIG. 2 is a front view thereof,

FIG. 3 is a back view thereof,

FIG. 4 is a left side view thereof,

FIG. 5 is a right side view thereof,

FIG. 6 is a top view thereof; and,

FIG. 7 is a bottom view thereof.

The broken lines represent parts of the beverage generating device as well as the boundary lines of the claim. None of the broken lines form part of the claim.

1 Claim, 6 Drawing Sheets(56)
